UNITED STATES PATENT OFFICE.

HERMAN VON BIELEFELD, OF WOODHAVEN, NEW YORK.

MATCH SAFE.

Application filed June 12, 1922. Serial No. 567,567.

To all whom it may concern:

Be it known that I, HERMAN VON BIELEFELD, a citizen of the United States, residing at Woodhaven, in the county of Queens 5 and State of New York, have invented certain new and useful Improvements in Match Safes, of which the following is a specification.

This invention relates to smokers' stands 10 and its object is to provide a combination match delivery and igniting mechanism.

Another object of the invention is to provide a cigar clipper actuated by the match delivering and igniting apparatus when set 15 in motion.

Still another object of the invention is to provide a device having a friction surface against which the heads of the matches are struck this surface being adjustable to engage 20 the heads of matches of varying lengths.

These and other analogous objects are attained by the novel design, construction and arrangement of parts hereinafter described 25 and shown in the accompanying drawings, forming part of this disclosure, and in which:—

Figure 1 is a perspective view of the combination smoker's stand and match delivering 30 apparatus.

Figure 2 is a vertical sectional view through the device illustrating in detail the match delivering apparatus.

Figure 3 is an enlarged sectional view 35 through a portion of the device taken at a right angle to Figure 2.

Figure 4 is a fragmentary detail plan view of the match holding device.

Figure 5 is a perspective view of the 40 lower end of the delivery hopper.

Figure 6 is a perspective view of the match straightening element.

Figure 7 is a vertical sectional view taken substantially on line 7—7 of Figure 3.

In the drawings, the numeral 10 designates the base of this improved smoker's stand, provided with a casing 11 which encloses the match reservoir and the delivery apparatus. Removably attached to the 45 base, near the front wall of the casing, is a cigarette humidor 12 and an ash receiver 13. A clip 14 extends upwardly from the cover 15 of the humidor 12 and may be used to hold cigars or cigarettes when they are not 50 in use.

A cigar containing cup 16 is inserted in

the cover of the casing, near one side edge, and a match reservoir 17 is inserted through the top of the casing 11, near the opposite side edge. As shown in Figure 1, the reservoir 17 is provided with a hinged cover 18 held in closed position by means of a turn button 19. The side walls of the reservoir 17 are provided with outwardly extending flanges 20, which serve to limit the downward movement of the reservoir through the top wall of the casing.

As shown in Figure 3, the bottom wall 21 of the match reservoir is inclined to form a hopper and a spring pressed follower 22 is arranged within the reservoir to force the matches contained therein downward and against the wall 21. Hingedly connected as at 23, to brackets 24 on the underside of the wall 21, is a plate 25, its forward end carrying an upwardly extending match straightening tongue 26, to which are secured resilient guide fingers 27, serving to force an individual match into the delivering apparatus as will be more fully hereinafter described.

Extending beyond one end of the free edge of the plate 25 is an actuating arm 28, provided with parallel fingers 29, between which is disposed an actuating pin 30, carried by a lever 31, pivoted at 31' to the inner side of the wall 32 of the casing 11 (see Figure 7).

Pivottally mounted at the mouth of the hopper, is a discharge and cut-off plate 33, 90 the inner edge 34 of which is upturned so that when the plate is in elevated position, as shown in Figure 3, a trough will be formed for the reception of a single match, and when the plate is lowered, the match 95 will be discharged and the upturned edge 34 will act to close the mouth of the hopper, thus preventing more than a single match being discharged into the delivery mechanism. The movement of the plate 33 is controlled by means of a pin 35 engaged by the upper edge of a cam 36 carried by the lever 31.

Secured to the inner face of the wall 32 is a stop 37, adapted to limit the downward movement of the plate 33 so that the match carried by said plate will be discharged into the slot 38 in the wall 32, and will fall into the grooved upper edge of the delivery arm 39 of the delivery mechanism.

This delivery arm 39 is best illustrated in Figure 2, and as shown, is pivotally mount-

ed at 40 between the walls 32 and 42 of the casing 11, which are spaced at a distance approximately the thickness of a match, so that as the match is delivered through the 5 slot 38, it will fall directly into the groove in the arm cushion elements 41 are secured in the casing to engage the front and bottom edges of the arm 39, as best seen in Figure 2. Pivotedly connected as at 43, is 10 a plunger 44, which projects upwardly through the top wall of the casing 11, and is provided with a knob or handle 45, by means of which the same is actuated. A retractile coil spring 46 is attached to the 15 delivery arm 39, and to the wall 32, acting to return the delivery arm to its lowermost position.

Pivotedly mounted as at 47, between the walls 32 and 42, is an arcuate, abrasive 20 member 48, designed to engage the head of a match during its upward movement, when in the delivery arm, to cause the match to ignite. As shown in Figure 2, this member 48 is yieldably held in the path of the head 25 of the match by means of a spring 49, and is adjusted by the screws 50, so that the abrasive member may be made to engage the heads of matches of varying lengths.

In order that the match upon ignition 30 may be held in position for removal after the delivery arm has returned to lowered position, the top plate 51 has a slot 52, and is provided with an offset notch 53 into which the match is forced by means of a 35 spring 54 mounted between the walls 32 and 42, as illustrated in the drawings, the same extending through a slot 55 in the plate 32.

A curved slot 56 is formed through the plate 32 through which extends a pin 57 40 rigidly carried at the lower end of the plunger bar 44, this pin operating in a recess 58 formed in the lever 31 so as to rotate the same upon depression of the knob 45, the lever turning on the pivot 31' to make contact with the pin 55, this arrangement being shown in Figure 7.

In operation, the matches are placed in the reservoir 17, beneath the follower 22, and consequently will fall to the bottom 21 50 of the hopper. Upon pressing downwardly upon the knob 45, the delivery arm 39 will swing on its pivot 40 and simultaneously the lever 31 will be swung on its pivot, so that the pin 30 will engage the uppermost 55 finger 29, causing the plate 25 to move up-

wardly, and the tongue 26 to likewise move upwardly through the slot 55 formed near the discharge opening of the hopper, thereby straightening the matches in immediate contact with the tongue and at the same 60 time causing the lowermost match to move outwardly through the mouth of the hopper and into the trough formed at the upturned edge of the plate 33.

This plate, by reason of contact of the 65 pin 35 with the upper edge 36 of the cam lever 31, has been swung into the position shown in Figure 3, so as to prevent further outward movement of the match, and when the delivery arm again returns to its lowermost position, it will be seen that the free edge of the plate 33 falls downwardly and onto the stop 37, so that the match will be delivered from the plate and through the 70 slot 38 into the trough in the upper edge of 75 the delivery arm.

Obviously when in this position and when the delivery arm is again moved by means of the plunger 44, the head of the match will be straight across the abrasive 80 member 48, and thus become ignited so that when the limited travel is reached the match will be in full flame and may be withdrawn from its position between the spring 54 and the wall of the notch 53.

While certain preferred embodiments of 85 this device have been shown and described, it will be understood that changes in the form, arrangements, proportions, sizes and details thereof, may be made without departing from the scope of the invention as defined in the appended claims.

Having thus described my invention, what I claim as new and desire to secure by Letters Patent, is:—

In a device of the class described, a delivery hopper, a delivery arm associated therewith, a match straightening and positioning means associated with the hopper to properly position the match for the reception of the delivery arm, means associated with the arm and hopper for frictionally engaging the head of the match during its delivery movement to cause the same to ignite upon delivery and means for holding the match in vertical position, said means preventing the recedence of the match.

In witness whereof I affix my signature.
HERMAN VON BIELEFELD.
